UNITED STATES PATENT OFFICE.

HORACE D. WILLIAMS, OF POPLAR BLUFF, MISSOURI.

DESIGN FOR A BOTTLE.

SPECIFICATION forming part of Design No. 26,429, dated December 22, 1896.

Application filed November 16, 1896. Serial No. 612,369. Term of patent 14 years.

To all whom it may concern:

Be it known that I, HORACE D. WILLIAMS, a citizen of the United States, residing at the city of Poplar Bluff, in the county of Butler, State of Missouri, have invented a new and original Design for Bottles, of which the following is a full, clear, and exact description, reference being had to the accompanying drawings, forming a part of this specification, ⁵ wherein—

Figure 1 is a front elevational view of a bottle embodying my invention. Fig. 2 is a side elevational view thereof.

This invention relates to a new and original design for bottles; and it consists in the ¹⁵ peculiar shape and configuration of the bottle.

As illustrated in the drawings, the design resides in a bottle the body portion of which is substantially cylindrical and configured to ²⁰ represent the bark of a tree.

The shoulder of the bottle is inclined, as

shown, while the neck, which is plain, extends upwardly in line with the body portion of the bottle and has formed on its upper end an outturned flange, the under face of which ²⁵ is beveled. On the front face of the bottle is a plain rectangular panel.

The essential features of the design are the shape and configuration of the bottle, substantially as herein shown and illustrated in ³⁰ the drawings.

What I claim is—

The design for a bottle, substantially as herein shown and described.

In testimony whereof I hereunto affix my ³⁵ signature, in presence of two witnesses, this 26th day of October, 1896.

HORACE D. WILLIAMS.
